UNITED STATES PATENT OFFICE.

DOROTHY B. SAVAGE, OF CAMBRIDGE, MASSACHUSETTS.

DESIGN FOR A DOLL.

Application filed March 21, 1922. Serial No. 1,319. Term of patent 3½ years.

To all whom it may concern:

Be it known that I, DOROTHY B. SAVAGE, of a doll, showing by new design, Figures 1 and 2 are front and rear views a citizen of the United States, residing at Cambridge, county of Middlesex, Commonwealth of Massachusetts, have invented a new, original, and ornamental Design for a Doll, of which the following is a specification, reference being had to the accompanying drawing, forming part thereof.

I claim:— The ornamental design for a doll, as shown.

DOROTHY B. SAVAGE.
